UNITED STATES PATENT OFFICE.

IRA L. VAN BUSKIRK, OF LOUISVILLE, KENTUCKY.

ELECTRIC-SWITCH-OPERATING APPARATUS.

No. 848,940.

Specification of Letters Patent.

Patented April 2, 1907.

Application filed September 13, 1906. Serial No. 334,483.

To all whom it may concern:

Be it known that I, IRA L. VAN BUSKIRK, a citizen of the United States, residing at Louisville, in the county of Jefferson, State 5 of Kentucky, have invented certain new and useful Improvements in Electric-Switch-Operating Apparatus; and I do hereby declare the following to be a full, clear, and exact description of the invention, such as will enable 10 others skilled in the art to which it appertains to make and use the same.

This invention has reference to electric-switch-operating apparatus, and has for its object the provision of a device to be used in 15 connection with an electric switch whereby the switch can be operated from any part of the building to break the circuit and cut off the supply of electricity to the motor, thereby stopping the same.

20 A further object of the invention is to provide a device of that nature which may be applied with equal facility to a switch having one or several poles.

To these ends the invention includes in 25 combination a switch adapted to be engaged when in closed position by a movable dog pivoted upon the switch-block, an electromagnet having a link attached to the hammer secured to its armature and connecting the 30 hammer and dog, a series of push-buttons circuited with the electromagnet and adapted upon depression to actuate the hammer and disengage the dog from the switch, and a spring adapted to throw the switch into open 35 position upon such disengagement.

The invention further consists in the construction and arrangement of the several parts, as hereinafter fully described, specifically claimed, and illustrated in the accompanying drawings, in which—

Figure 1 is a view of a building fitted with the improved switch-operating apparatus; Fig. 2 is a front elevation of the apparatus, showing a single-pole switch. Fig. 3 is a side 45 view of Fig. 2. Fig. 4 is an enlarged view of the locking-dog. Fig. 5 is a front elevation of the apparatus, showing a bipolar switch. Fig. 6 is a back view of Fig. 5, showing the wiring. Figs. 7 and 8 are vertical sections 50 on the lines 7 7 and 8 8 of Fig. 5.

Like parts are designated by corresponding reference-numerals in the several views.

Referring to the drawings, and particularly to Figs. 2, 3, and 4, the box 10 carries 55 upon its front face the switch 11, connected to the main supply by the wires *a* and having

in the present instance a single pole or blade 12, fulcrumed in the bracket 13 and fitting in the jack 14 when in closed position. The switch-block, to which the bracket and jack are secured, is provided adjacent the latter with a movable L-shaped dog 15, having a shoulder at one end adapted to engage the outer edge of the switch-pole when the switch is closed, the opposite end of said dog being 60 connected by a link 16 with a hammer 17, secured to the armature 18 of an electromagnet 19, inclosed by a casing secured to the box side, there being a bell 20 located upon the box side in position to be struck upon movement of the hammer. A push-button 21 is 65 circuited with the electromagnet through the wires *b*, there being a plurality of push-buttons located within the different rooms of the building, as shown in Fig. 1, as many push-buttons being used as desired. A U-shaped 70 spring 22 is secured to the upper portion of the switch-plate, the arms of said spring extending on opposite sides of the switch-pole and its bight portion bearing against the inner face thereof, the spring tending to swing the switch upwardly into open position upon the disengagement of said dog therefrom. The switch is connected to the motor 23 by 75 the wire *c*, while the battery 24, located within the box 10, is connected with the electromagnet by the wires *d* and with the push-buttons by the wires *e*. It will thus be seen that by depressing any one of the push-buttons and the consequent completion of the 80 circuit the movement of the hammer 17, connected to the armature of the electromagnet, will effect the release of the dog 15 from the switch through the medium of the link 16, the spring 22 swinging the switch upwardly 85 into open position immediately upon such disengagement, thus breaking the main circuit and stopping the motor, the sounding of the bell 20 indicating such stoppage. 90

In Figs. 5 to 8 there is shown a slightly modified construction in which a bipolar switch 11' is used, the switch comprising the poles or blades 12', fulcrumed in the brackets 13' and fitting in the jacks 14' when in closed position, the opposite ends of the poles being connected by the cross-piece 25, of insulating material, provided with a handle 26. Located between the switch-poles is a movable dog 15', pivotally mounted in a bracket secured to the switch-plate and provided with a shoulder at its upper end similar to that on the dog 15, the shoulder engaging a lip 27. 100 105 110

secured to the cross-piece, when the switch is in closed position. The dog is actuated by a link 16', connected at one end thereto and provided at its opposite end with a hook 29, 5 engaged within an eye 30, formed on one end of a strap 31, secured to the hammer 17', attached to the armature 18' of the electromagnet 19', the casing of which is broken away at one corner to permit the movement of hammer. Strap 31 is disposed at right angles to the hammer, as shown. The electromagnet is connected by the wires d' to the battery 24', while the switch is connected to the main supply by the wires a' and to the motor by the wires c' . The switch, electromagnet, and cells in the present instance are carried by a plate 32, attached in any desired manner to the wall of the building, one of the push-buttons 21' being likewise secured thereto and connected to the battery 24' and electromagnet 19' by the wires e' and d' . The plate also carries a second push-button 33, connected by the wires f and g , respectively, to the battery 24' and gong 34. One 25 of the switch-poles is engaged by an actuating-spring 22', similar to spring 22 in appearance and used for a similar purpose, while the opposite pole is engaged when the switch is swung upwardly by a spring 35, thus limiting 30 such movement and preventing the switch-pole from injury by contact with the electromagnet-casing. Depression of any one of the push-buttons 21' will effect the release of the dog 15' from the lip 27 of the cross-piece 35 25, when the spring 22' will operate as described in connection with the first-mentioned construction, the spring 35 limiting the upward movement of the switch, as above stated. Owing to the quick make-and-break connection between the electromagnet 19' and its armature 18', the strap 31, carried by the hammer 17', will be given a series of short vibrations in rapid succession, thus effecting the release of the dog from the 40 switch-lip and consequent movement of the switch, the lost motion occasioned by the movement of the hooked end of the link 16' within the strap-eye insuring such release, even though the battery be to some extent 45 run down, in which condition the disengagement of the switch is impossible where the armature is connected directly to the dog, and a slow make-and-break connection is made use of. The gong 34 serves as a caution-bell and is sounded prior to closing the switch and starting the motor, it being understood that there are in actual use a plurality of such gongs located in the several 50 rooms of the building or buildings and connected in series, the depression of the push-button 33 sounding all of said gongs simultaneously. The electromagnet 19' is provided with a bell 20' in position to be struck by the hammer 17'.

65 Modifications and changes in construction

may obviously be made within the scope of the claims, as the invention is not intended to be limited to the exact details shown and described. It is to be understood, moreover, that the connection-link 16 and hammer 17 70 is such as to effect a rapid vibration of dog 15', similar to that of the dog 15', the quick make-and-break connection being made use of.

What is claimed is—

1. The combination, with an electric 75 switch, of a vibratory dog adapted to engage the switch when the latter is closed; an electromagnet, including an armature; a link connecting said armature with said dog; a series of push-buttons circuited with said 80 electromagnet, and adapted, upon depression, to vibrate said dog to release the same from engagement with said switch through the link connection between said dog and armature; and a spring connected with said 85 switch, and adapted to throw the same into open position when said dog has been actuated.

2. The combination, with an electric switch, of a movable dog adapted to engage 90 the switch when the latter is closed; an electromagnet including an armature; a hammer secured to said armature; a bell located adjacent said hammer, in position to be struck thereby; a link connecting said hammer with 95 said dog; a series of push-buttons circuited with said electromagnet, and adapted upon depression to release said dog from engagement with said switch; and a spring connected with said switch, and adapted to throw 100 the same into open position when said dog has been actuated.

3. The combination, with an electric switch, of a vibratory dog mounted upon the switch-block and adapted to engage the 105 switch when the latter is in closed position; an electromagnet including an armature; a hammer secured to said armature; a strap secured to said hammer at right angles thereto, said strap having an eye formed in its free end; a 110 bell located adjacent said hammer in position to be struck thereby; a link having a hook at one end for engagement with said eye, and connected at its opposite end with said dog; a series of push-buttons, circuited with said electromagnet, and adapted, upon 115 depression, to vibrate said dog to release the same from engagement with said switch through the link connection between said dog and armature; and a spring connected 120 with said switch, and adapted to throw the same into open position when said dog has been actuated.

4. The combination, with an electric switch, comprising spaced blades, a connecting cross-bar, and a lip secured to the latter, of an electromagnet including an armature; a dog pivotally mounted upon the switch-block and adapted to engage said lip when the switch is in closed position; a link con- 125 130

necting said armature and dog; a series of push-buttons circuited with said electromagnet, and adapted upon depression, to release said dog from engagement with said lip through the link connection between said dog and armature; a spring bearing against one of said blades and adapted to swing said switch into open position; and means adapted to contact with the opposite blade, to limit such swinging movement.

5. The combination, with an electric switch, comprising spaced blades, a connecting cross-bar, and a lip secured to the latter intermediate the ends thereof; of an electromagnet including an armature; a dog pivotally mounted upon the switch-block between said blades, and adapted to engage said lip, when the switch is in closed position; a ham-

mer secured to said armature; means connecting said hammer and dog; a series of 20 push-buttons circuited with said electromagnet, and adapted, upon depression, to release the dog from engagement with said lip through the connecting means between said hammer and said dog; a spring adapted 25 to engage one of said blades to swing said switch into open position; and a spring adapted to contact with the opposite blade, to limit such swinging movement.

In testimony whereof I affix my signature 30 in presence of two witnesses.
